UNITED STATES PATENT OFFICE

WALTER N. VANCE, OF CHICAGO, HEIGHTS, ILLINOIS, ASSIGNOR, BY MESNE ASSIGNMENTS, TO LYON METAL PRODUCTS, INCORPORATED, OF AURORA, ILLINOIS, A CORPORATION OF ILLINOIS.

LOCKING DEVICE

Application filed April 2, 1928. Serial No. 268,595.

This invention relates in general to latch or locking devices for sheet metal lockers and the like, and has more particular reference to the provision of a new and improved latch construction of the automatic character wherein the mere closing of the door results in the locking of the locker or other compartment.

The principal object of the invention is the provision of a latching and locking mechanism adapted to operate automatically upon the mere closing of the door, which will be more silent in its action than constructions heretofore generally employed.

Another important object of the invention is the provision of a construction of the character set forth, which will require the mere turning of the key and a light pull upon the key itself to open the door.

A further object of the invention is the provision of a device of the character described, the parts of the latching devices of which will be so constructed and arranged that when the lock is moved to release position they tend to disengage and start the door in its opening movement.

Another object of the invention is the provision of a structure possessing these and other advantages, which while capable of valuable use in other constructions, particularly adapts itself to incorporation in coat and other lockers constructed largely or entirely of sheet metal.

Numerous other objects and advantages of the invention will be apparent from the following description, which, taken in connection with the accompanying drawings, discloses a preferred embodiment thereof.

Referring to the drawings,

Figure 1 is a rear elevation of a door and door frame, the locking and latching devices being shown in locked position;

Figs. 2 and 3 are sections taken substantially upon the line 2-2 of Fig. 1, showing the parts in locked and unlocked relation and on somewhat enlarged scale;

Figs. 4 and 5 are enlarged partial details of the latching mechanism, the views being taken similarly to Fig. 1;

Figs. 6, 7, 8 and 9 are sections taken re-

spectively on the lines 6-6, 7-7, 8-8 and 9-9 of Fig. 4.

For the purpose of illustrating my present invention, I have shown on the drawings a locker door member 11 pivotally mounted at 12 in a door frame member 13, which may be taken to constitute the front of a sheet metal locker. In the present instance, the door frame is constructed in a usual and well-known manner, flanges 14 being arranged to form the outer face of the frame about the door opening. The door is preferably of sheet metal and is provided with an inturned flange 15 extending about its periphery.

The locking device comprises, in general, a bar or slide 16, slide engaging keepers 17 (one located adjacent the top and one located adjacent the bottom of the door frame 13), a locking keeper 18, and a lock 19. The slide 16 is provided with projections 21 at its ends, these projections being flat and arranged to extend away from the flange 15 and at an angle to the longitudinal axis of the slide. The slide is mounted upon the flange 15 and to move vertically with respect thereto as an incident to the opening and closing of the door. It is held in place upon the flange 15 by lugs 22 struck up from the material of the flange and having enlarged heads 23 arranged through slots 24 in the slide 16. The particular construction and arrangement of the lugs 22 and slots 24 forms no part of the present invention, and a more particular description of them will not, therefore, be undertaken.

The slide engaging keepers 17 are of strip metal material and are spotwelded or otherwise secured at 25 to the inner face of the flange 14 of the angle frame member. Each keeper 17 is bent at 26 to extend back in parallelism with the flange 15 of the door and thence at 27 and 28 to provide a part arranged on the opposite side of the flange 15, so that upon the closing of the door the flange 15 is arranged within the keeper. Each keeper 17 is provided with an angularly disposed or inclined slot 31, adapted to receive an appropriate inclined projection or lug 21 upon the closing of the door.

The parts are so constructed and arranged

that as the door is closed the lugs 21 engage the material of the keepers beneath the slots 31, the material above the slots being cut away at 32. Thus constructed, a lip or lug 33 is presented in the path of inward movement of each lug 21, causing the lug to ride up the lower inclined surface 34 of the slot from the position shown in Fig. 3 to that shown in Fig. 2. This movement results in the bodily lifting of the slide and arranges the parts in interlocked relation, the lugs 21 being then disposed behind the parts 35 of the keepers above the slots.

The lock 19 is preferably of the spring lock type and is secured upon the door at 41, with its barrel 42 which receives the key arranged through the usual barrel opening of the door. Slide 16 is provided with an offset part 43 adjacent the bolt 44 of the lock, and this offset part is provided with an opening 45 through which the bolt is projected when the slide is raised into the locked position shown in either Fig. 2 or Fig. 4. The lock, therefore, holds the slide in upper position with the keepers 17 and the slide interengaged. The keeper 18 which is provided at the lock and secured upon the frame angle flange 14 at 46 is of the general shape of a keeper 17, except that its loop portion is narrower and embraces merely the flange 15 of the door, extending between this flange and the offset portion 43 of the slide. The keeper itself is provided with a slot 47 into which the bolt 44 extends when in locked position, as may be seen in Fig. 8. The bolt of the lock, therefore, engages both the slide 16 and the keeper 18.

It will be manifest that in locking the door the lugs 21 and the keepers 17 engage in merely sliding contact and the parts are moved quietly into final relation, producing a latch of peculiarly silent action. The door is held against outward opening movement at the three keepers and at these same points is restrained against separation from the frame in the plane of the door to prevent springing of the lock.

The material of the slide or bar 16 is preferably curved transversely throughout portions of its length at 51 to stiffen it and insure rigidity.

It will be manifest that in opening the locker the weight of the slide 16 tends to move the lugs 21 down and out of the slots 31 in turn tending to open the door, so that assuming the slots to have a rather sharp angularity little or no pull is required to start the door on its opening movement. It will be manifest moreover that no outside manipulation other than the turning of the key is necessary to disengage the latching device, and that no outside manipulation at all is necessary to the closing and latching of the door, the door being merely pushed shut.

The present invention has the claims there-

of limited to the specific locking construction herein shown, the claims being limited to the slotted keepers.

It is thought that the invention and many of its attendant advantages will be understood from the foregoing description, and it will be apparent that many changes may be made in the form, construction and arrangement of the parts without departing from the spirit and scope of the invention or sacrificing all of its material advantages, the form hereinbefore described being merely a preferred embodiment thereof.

I claim:

1. The combination with a locker, a door for said locker, and a door frame on said locker in which said door is pivotally mounted, of a bar mounted in vertical position on said door and having parts angularly arranged with respect to the door edge, keepers arranged on the door frame inside of said locker and having angularly arranged slots for receiving the angularly disposed portions of said bar, closing of the door causing the angularly arranged parts of the bar to move through the angular slots of said keepers and into interengaging relation therewith.

2. The combination of a door, a door frame in which said door is pivotally mounted, a bar mounted in vertical position on said door and having parts angularly arranged with respect to the door edge, keepers arranged on the door frame and having angularly arranged slots for receiving the angularly disposed parts of said bar, closing of the door causing the angularly arranged parts of the bar to move through the angular slots of said keepers and into locked relation therewith, and a locking device engaging said bar for keeping said angularly disposed parts in said slots and in locked relation.

WALTER N. VANCE.
